WITNESS:

UNITED STATES PATENT OFFICE.

FRANK L. DECKER, OF KIMBLE, PENNSYLVANIA.

BUILDING FORM.

Original application filed June 21, 1924, Serial No. 721,542. Divided and this application filed January 21, 1925. Serial No. 3,858.

To all whom it may concern:

Be it known that I, FRANK L. DECKER, a citizen of the United States, residing at Kimble, in the county of Pike and State of Pennsylvania, have invented new and useful Improvements in Building Forms, of which the following is a specification.

This is a division from my co-pending application, Serial No. 721,542, upon im-

10 proved building forms, filed June 21, 1924.

My mentioned application has reference to a building construction in which grooved stone or concrete slabs are held in spaced relation to provide the inner and outer walls 15 of a building, and in which mortar is delivered through the holding means between the joints of the slabs.

My present invention has reference to a similar construction, but is designed to provide a means whereby the concrete or stone 20 slabs may be employed as a facing for buildings already erected and in which the slabs are held in vertical courses by a metal superstructure which provides a means for directing mortar between the joints of the slabs, and also provides a mold for holding the set mortar against the joints of the slabs.

The drawings which accompany and form 25 part of this application, illustrate a satisfactory embodiment of the improvement, and wherein:—

Figure 1 is a side elevation of a wooden building refaced in accordance with this 30 invention.

Figure 2 is a horizontal sectional view approximately on the line 2—2 of Figure 1.

Figure 3 is a vertical transverse sectional view approximately on the line 3—3 of 35 Figure 1.

Figure 4 is a perspective view of one of the horizontal plates which connect the vertical plates.

Figure 5 is a similar view of another horizontal plate employed.

Figure 6 is a perspective view of one of the inner wall plates.

Figure 7 is a similar view of one of the spacer plates.

50 My invention contemplates a means whereby a slab face may be arranged upon a frame building construction. The siding of the building is taken off, and there are secured to the uprights or studding courses of horizontally disposed plates 31. The inner

edges of these plates are formed with upturned flanges 32, and these flanges are connected directly to the building structure 33. The plates, from their flanged edges, have their sides arranged at an outward angle 60 and are flanged, as at 34. The outer straight edges of the plates are flanged, as at 35. The plates at the said flanged ends are slotted both longitudinally and transversely, and the metal bounded by these slits provides spaced flanges 36 disposed at an opposite angle to the flanges 35 and with lugs or flanges 37.

The upper and lower plates employed are of a construction as above described, but the 70 upper plate is centrally formed with a substantially rectangular opening 37 and with slots 38 at the sides of the opening. The lower plate is provided with slots 39 designed to align with the slots 38. The 75 flanges 35 and 36 are received in the grooves in the superimposed slabs, the lugs 37 spacing the said slabs so that mortar can enter the grooves.

To provide a directing element for the 80 mortar, I employ a channeled member broadly indicated by the numeral 40 and substantially similar to the channeled members 3. This member 40 has its sides provided with upper tongues 41 and lower tongues 43. The member in a line with the inner edges of its tongues has upper slots 43 and lower slots 44. The channeled members are straddled by spaced angle arms 45—45 provided with angle ends 46 of 90 spacer plates 47. The arms of the spacer plates enter the lower slots 44 and may also, if desired, enter the upper slots 43 of the members 40. The lower tongues 43 pass through the slots 39 of the lower plates 95 31, and the tongues 41 pass through the slots 38 of the upper plates 31. The spacer bars are in the nature of right angular members, and at a distance from their arms 45, are provided with oppositely directed arms 48.

These arms may contact with the building 100 33. The outer horizontal flanged portion 49 of the spacer plate is preferably formed with an upstanding flange 50 to catch the mortar poured through the opening 37. The ends of the spacer plate are also provided with downwardly directed fingers 51 to be received in the slots of the adjacent channeled members 40.

With a construction as above described, 110

it will be noted that a block facing may be readily applied to an old frame building construction with a minimum amount of labor and material.

- 5 The metal superstructure remains a part of the building construction and it will be apparent that mortar poured in the channeled portions thereof will enter both the vertical and longitudinal grooves between 10 the slabs to effectively secure the slabs together. The mortar is preferably, but not necessarily, in the nature of a cement mixture so that when the same hardens it becomes concrete, and the superstructure provides a mold for holding such mortar or concrete when set.

While it is believed that the foregoing description, when taken in connection with the drawings, will fully set forth the details of my construction and the advantages thereof, it is to be understood that I am not to be restricted to the precise structural details disclosed, but am entitled to all such changes therefrom as fairly fall within the 25 scope of what I claim.

Having described the invention, I claim:—
A means for re-facing a wooden structure

in which the siding is removed therefrom, in which an outer wall construction comprising grooved slabs arranged in superimposed courses having their vertical joints broken are employed, of horizontally disposed plates having inner flanged ends secured to the structure and outer ends which are flanged in both directions, one of the last mentioned flanges comprising spaced elements and both of the last mentioned flanges designed to be received in the grooves of the superimposed slabs, other flanges on the plates holding the slabs in spaced relation, a channeled member secured to the lower plate and passing through the upper plate of each series, a spacer plate for the channeled members engaging therewith and engaging with the mentioned plates, and said channeled members being disposed along the vertical joints of the wall and serving as a passage for concrete to be delivered between the joints of the slabs, and also as a mold for such concrete when set.

In testimony whereof I affix my signature.

FRANK L. DECKER.
